IRONING TABLE

Gilbert C. Gettelman, Milwaukee, Wis., assignor to Geuder, Paeschke & Frey Co., Milwaukee, Wis., a corporation of Wisconsin

Application March 1, 1955, Serial No. 34,796

Term of patent 14 years

(Cl. D49—1)

Fig. 1 is an end view of an ironing table showing my new design in its workable position;

Fig. 2 is a side view of the table;

Fig. 3 is a side view of the table when collapsed; and
Fig. 4 is a bottom view of the table when collapsed.

I claim:

The ornamental design for an ironing table, as shown.
